SANITARY APPARATUS

Robert F. Bracke, Arlington Heights, Ill., assignor
to R. F. Bracke & Company, Chicago, Ill., a
partnership composed of Robert F. Bracke and
Robert Anderson

Application July 17, 1941, Serial No. 402,745

11 Claims. (Cl. 4—222)

My invention relates to sanitary apparatus which is more particularly adapted for but not limited to use in the lavatories of industrial establishments employing women who handle food stuffs or other articles which are to be protected against contamination.

An object of my invention is to provide sanitary apparatus which will make it necessary for a person to disinfect her hands after using the toilet facilities of such an establishment.

An object of my invention is to provide sanitary apparatus of the foregoing type which is inexpensive to manufacture and install, trouble free in use, and may be easily applied to existing toilet facilities.

Another object of my invention is to provide sanitary apparatus which may be readily cleaned and maintained in perfect condition.

Another object of my invention is to provide novel means for requiring a person to disinfect both hands.

Another object of my invention is to provide a novel arrangement of disinfectant basin and switch mechanism associated therewith.

Other objects and advantages will become apparent as the description proceeds.

In the drawing,

Fig. 1 is a diagrammatic view showing a preferred form of my invention applied to the toilet facilities of an industrial establishment or similar concern.

Fig. 2 is a front elevation of the disinfectant basin and switch mechanism associated therewith.

Fig. 3 is a vertical sectional view taken on the line 3—3 of Fig. 2.

In Fig. 1, I have diagrammatically shown that part of a lavatory of the kind commonly found in industrial establishments comprising the toilet stalls 10, 11 and 12, each containing a conventional toilet 13. Each stall has a door 14, pivotally supported on one or more hinges 15 and provided with a spring 16 for swinging each door to open position.

Each door is adapted to be held in closed position by a sliding latch 17, urged outwardly to door engaging position by a spring 18, it being understood that the latch 17 and spring 18 are suitably supported on each door frame adjacent a door opening. Each door is illustrated as being provided with a U-shaped bracket 19 for receiving the latch 17 when the door is in closed position.

It will be noted that the latches 17 are outside of the toilet stalls and are not accessible from

the interior thereof. Each latch is provided with a solenoid 20 which, when energized, serves to retract its associated latch 17 and permit the door thus released to be swung to open position by its spring 18. Each solenoid is adapted to be connected to a suitable source of electrical energy through a pair of switches 21 and 22 associated with a disinfectant basin 23 in such manner that the employee must dip both hands into the disinfectant in the disinfectant basin in order to operate these switches and thus effect opening of the door 14.

Referring particularly to Figs. 2 and 3, it will be seen that I have provided a basin 23 which may be made of any suitable material but which I preferably make of cast iron or sheet steel suitably enameled. This basin is provided with openings for receiving the screws 24 whereby the basin may be firmly attached to a stationary wall of the stall in such manner that opening and closing of the door will not result in splashing or loss of disinfectant from the basin. A suitable drain plug 25 is preferably provided in the lowermost part of the basin to permit complete drainage thereof when desired.

An L-shaped bracket 26 is attached to the upper part of the basin, as by screws 27, and carries the switches 21 and 22. In the embodiment illustrated, these switches are push button switches of an inexpensive kind, readily available on the open market, and are mounted in suitable apertures provided in the bracket 26. The switches 21 and 22 are pushed upwardly through these apertures and are retained in place by spring retainers forming unitary parts of the push button switches. The lead wires for the switches pass through an opening 28 and downwardly in slot 29 formed in that portion of the basin which engages the supporting wall.

Switches 21 and 22 are enclosed by a removal cover 30 secured in place by bolts 31, or any other suitable attaching means. This cover provides aligned openings 32 and 33 for each switch operating pin 34. Each of these pins has an enlarged head 35 at its lower end and adjacent the bottom of the basin and each pin is provided with a transverse opening for receiving a cotter pin 36, which determines the normal position of its associated switch operating pin.

Before leaving a stall, an employee immerses her hands in the basin 23 and places her fingers beneath the switch operating pins 34 and raises them simultaneously to operate the switches 21 and 22 and thus close the circuit through the associated solenoid 20. This solenoid thereby with-

draws its latch 17 whereby the door of the stall is swung open by spring 16. The cover 30 is provided with a web 37 which is located intermediate the switch control pins 34, so that both pins can not be operated by one hand.

Particular attention is called to the fact that the cover 30 may be readily removed to permit inspection and cleaning of the switch operating pins and that part of the basin normally rendered inaccessible when this cover is in position. Such removal and subsequent replacement of the cover 30 does not disturb the switches 21 and 22 or the electrical connections therefor. This is important since maintenance of the fluid level in the basins and cleansing of such basins will normally be taken care of by people with no knowledge of or familiarity with electrical mechanisms.

Referring particularly to Fig. 1, it will be seen that the solenoids 20 are supplied with electrical energy from the secondary winding 38 of a transformer 39. The primary winding 40 of this transformer may be connected to the usual lighting circuit of the factory, such as the ordinary 110 volt circuit. In order to protect the employees against dangerous or unpleasant shocks, the transformer 39 is preferably so designed that the voltage in the solenoid circuits is in the order of 10 to 24 volts, as I have found such voltage is ample to operate the solenoids 20.

It is desirable to have some means in addition to the switches 21 and 22 for withdrawing the latches 17. This may be accomplished by providing each latch with a handle or other part which can be readily gripped by a person outside the stalls to withdraw any desired latch. I have found it desirable, however, to provide an electrical switch 41 outside each stall, and preferably mounted on the door frame thereof, for controlling the solenoid 20 of such stall independently of the switches 21 and 22. As shown in Fig. 1, each switch 41 is mounted in parallel with the set of switches 21 and 22 for controlling its solenoid 20.

I have also shown one master release switch 42 arranged in parallel with all of the switches 41 and adapted simultaneously to energize all of the solenoids 20, thus withdrawing all of the latches 17 and permitting any and all of the closed doors to be swung to open positions by spring 16.

The several disinfectant basins 23 are designed to be kept clean and filled with suitable disinfectant up to approximately the level shown in Fig. 3. After an employee has used a toilet, she will immerse both hands into the disinfectant and raise the switch control pins 34, thereby closing both switches 21 and 22 associated with that particular basin. This, in turn, energizes the solenoid 20 in circuit with such switches and causes such solenoid to withdraw its latch 17. The door 14 of that particular stall is then swung to open position by its spring 16, whereupon the employee may leave the stall and return to her duties.

As soon as the employee withdraws her fingers from beneath the switch control pins 34, these pins drop downwardly under their own weight and the associated switches 21 and 22 return to their normal open positions. The latch 17 is thereupon returned to its inward position by its associated spring 18. The door engaging end of the latch 17 is beveled, as clearly shown in Fig. 1, so that when the door is next closed the bracket 19 can pass the latch 17 and be re-engaged thereby to hold the door in closed position.

A valuable feature of my arrangement of parts

lies in the fact that both the basin and solenoid are located on stationary walls so that it is unnecessary to provide wiring connections across pivoted or other movable joints, such as would be necessary if either of these devices were located on the door or other movable partition.

While I have illustrated and described only one embodiment of my invention, it is to be understood that my invention can assume numerous forms and that the scope of my invention is described in the following claims.

I claim:

1. In apparatus of the class described for controlling the opening of a door of a toilet compartment, the combination of a disinfectant basin mounted upon an inside stationary wall of such compartment, a latch for holding the door of such compartment in closed position, a solenoid for withdrawing said latch, a spring for opening said door, a pair of switches connected in series and controlling the supply of electrical energy to said solenoid, and operating means for said switches located adjacent the bottom of said basin and well beneath the normal level of liquid therein, said operating means adapted to be engaged by a person's hand only when immersed in said liquid.

2. In apparatus of the class described for controlling the opening of the door of a toilet compartment comprising a disinfectant basin inside the compartment, a pair of switches associated therewith, a solenoid latch release for the door of said compartment connected in series with both of said switches for permitting opening of the door upon operation of the solenoid, a pair of switch operating means located adjacent the bottom of said basin and well beneath the normal level of the liquid therein for operating said solenoid, and a partition in said basin separating said switch operating means.

3. In apparatus of the class described for controlling the opening of the door of a toilet compartment comprising a latch for said door mounted in said compartment, a door latch inaccessible to manual operation from inside said compartment, a solenoid for releasing said latch to permit opening of the door, a pair of switches connected in series with said solenoid for effecting operation of the latter to release said latch, and switch operating means mounted on the rear wall of said basin, said operating means having hand engaging portions located close together and well beneath the normal liquid level of said basin.

4. In apparatus of the class described for controlling the opening of the door of a toilet compartment comprising a latch for said door inaccessible from the inside of said compartment, a liquid disinfectant basin located in said compartment, a bracket provided by said basin, means including a pair of switches mounted on said bracket operable to effect release of said latch, a removable cover for said switches, and switch operating means mounted in said cover and having hand engaging portions extending therebeyond to locations beneath a normal liquid level in said basin.

5. In apparatus of the class described for controlling the opening of a door of a toilet compartment comprising a latch for said door inaccessible from the interior of said compartment, a liquid disinfectant basin mounted in said compartment, a pair of switches associated with said basin and connected in series and operable to release said latch, a cover for said switches,

means including manually operable parts extending beneath the normal liquid level in said basin for operating said switches, and a partition carried by said cover to prevent one hand operation of both said parts.

6. In apparatus for compelling a person to disinfect the hands, a liquid disinfectant basin, means for attaching said basin to a support, control means, a pair of switches mounted adjacent the rear wall of said basin simultaneously operable to effect operation of said control means, an opening and a groove provided in said rear wall to permit wiring connections for said switches to extend through said wall and downwardly between said wall and said support, 15 a box-like cover for said switches, a switch operating pin for each switch, guide means provided by said cover for said operating pins, and a partition provided by said cover and extending intermediate said operating pins preventing one hand operation of both of said pins and operation of said switches to operate said control means.

7. In apparatus for compelling a person to disinfect the hands, the combination of a basin for holding a quantity of disinfectant liquid, a control circuit, a pair of normally open switches associated with said basin and connected in series in said circuit, switch operating means for said switches having manually engageable parts located in said basin beneath the normal liquid level thereof, and means for preventing one hand operation of both of said operating means, whereby both hands must be immersed in the disinfectant liquid to operate said switches into said predetermined positions. 35

8. In apparatus for compelling a person to disinfect the hands, the combination of a basin for holding a quantity of disinfectant liquid, a switch mounted in proximity to the basin, a 40 removable cover for said switch extending below the liquid level in the basin, and switch operating means carried by said cover and having a

manually manipulatable part located in said basin and engageable only beneath said liquid level.

9. In apparatus for compelling a person to disinfect the hands, the combination of a basin for holding a quantity of disinfectant liquid, switch means mounted in proximity to said basin, manual operating means for said switch means, said operating means being positioned in said basin for manual actuation and accessible only below the normal liquid level to require immersion of two hands in the disinfectant liquid thereof, and a control circuit controlled by said switch means.

10. In apparatus for compelling a person to disinfect the hands, the combination of a basin for holding a quantity of disinfectant liquid, manually operated means in said basin extending below the normal liquid level and requiring immersion of two hands in the liquid in the basin for manual actuation, a door opening control mechanism remote from said operating means and basin, and means connecting said door opening control mechanism and said operating means for rendering said operating means effective to operate said control mechanism to condition said door for opening. 20

11. In apparatus for compelling a person to disinfect the hands, the combination of a basin for containing a quantity of disinfectant liquid, manually operated means located below the level of liquid in said basin as to be actuatable only by a hand immersed in the liquid therein, operable means remote from the basin and the operation of which is necessary or desirable from the standpoint of a person using said basin, remote control means associated with said last-mentioned means for effecting operation of said operable means, and an operative connection between said remote control means and said manually operated means. 30

CERTIFICATE OF CORRECTION.

Patent No. 2,319,034.

May 11, 1943.

ROBERT F. BRACKE.

It is hereby certified that error appears in the printed specification of the above numbered patent requiring correction as follows: Page 2, second column, line 43, claim 3, for "a latch for said door" read --a liquid disinfectant basin--; and that the said Letters Patent should be read with this correction therein that the same may conform to the record of the case in the Patent Office.

Signed and sealed this 6th day of July, A. D. 1943.

Henry Van Arsdale,
Acting Commissioner of Patents.
